United States Patent [19]

Makinson et al.

[11] Patent Number: Des. 294,565

[45] Date of Patent: ** Mar. 8, 1988

[54] VOLTAGE TRANSFORMER

[75] Inventors: David N. Makinson, Franklin, N.C.;
Karl W. Struck, Clayton, Ga.

[73] Assignee: Sangamo Weston, Inc., Norcross, Ga.

[**] Term: 14 Years

[21] Appl. No.: 928,372

[22] Filed: Nov. 10, 1986

[57] CLAIM

The ornamental design for a voltage transformer, as
shown and described.

DESCRIPTION

FIG. 1 is a perspective view of a voltage transformer
showing our new design;

FIG. 2 is a rear elevational view thereof;

FIG. 3 is a side elevational view thereof, the opposite
side being a mirror image; and

FIG. 4 is a bottom plan view thereof.
